UNITED STATES PATENT OFFICE.

JOSEPH L. COX, OF BATTLE CREEK, MICHIGAN, ASSIGNOR TO THE DUPLEX PRINTING PRESS COMPANY, OF SAME PLACE.

ROTARY INK-FOUNTAIN FOR PRINTING-PRESSES.

SPECIFICATION forming part of Letters Patent No. 463,103, dated November 10, 1891.

Application filed January 17, 1891. Serial No. 378,101. (No model.)

To all whom it may concern:

Be it known that I, JOSEPH L. COX, of Battle Creek, in the county of Calhoun and State of Michigan, have invented certain new and useful Improvements in Rotary Ink-Fountains for Printing-Presses; and I do hereby declare that the following is a full, clear, and exact description thereof, reference being had to the accompanying drawings, and to the letters of reference marked thereon, which form part of this specification, in which—

Figure 1 is a transverse sectional view of my improved combined ink-fountain and distributing-roll and ductor-roller. Fig. 2 is an end view, and Fig. 3 a detail side elevation, thereof, illustrating a means for operating the ductor-roller. Fig. 4 is a detail view.

This invention is an improvement in rotary ink-fountains for printing-presses; and it consists in the novel construction and combination of parts, hereinafter clearly described and claimed.

Referring to the drawings by letters, A designates a hollow roll or cylinder, having trunnions or shafts by which it can be suitably journaled in the frame of a printing-press, and one of said trunnions *a* is hollow and is preferably connected with an ink-reservoir to supply ink to the interior of the cylinder by a force-pump and pipes (not shown) or in any other suitable manner. The roll has a longitudinal slot *b* in it, which slot is closed by a roller *B*, journaled in the end walls of the cylinder, the periphery of roller *B* projecting evenly with the periphery of roll *A*. The roll *A* is revolved by any proper means, (not shown,) so that the ink in the interior thereof is thrown outward against the shell thereof by centrifugal action and against roller *B*, which as the roll revolves will deliver a small quantity of ink to the distributing-rollers *D* *D*, journaled beside the roll *A* and running against the face thereof, which thus forms a distributing-roll for disseminating the ink, as well as a supply-fountain. The form-rollers (not shown) may be arranged to contact with roll *A* or the distributing-rollers *D*, as may be desirable. I preferably positively rotate roller *B*, which I call the "ductor-roller," at intervals, so as to regulate the quantity of ink de-

livered to the distributing-rollers. One means of doing this I show herein.

One journal of roller *B* projects beyond the end of the roll and on it is fixed a ratchet *C*, which is engaged by a dog or brake-spring *c* 55 to prevent casual rotation of the roller.

L designates a spring-controlled dog engaging ratchet *C* and carried by a swinging arm *M*, hung on the journal of roller *B* or on a stud projecting from the end of roll *A*, so that it 60 can be oscillated to gradually revolve the roller *B*. The arm *M* is connected by a pitman *K* with a crank-pin *k*, preferably adjustably connected to a gear *J*, journaled on a stud *j* on the end of the roll. Gear *J* meshes with a 65 small pinion *i* on a sleeve mounted on a stud *h*, fixed on the end of the roll, and on the outer end of said sleeve is fixed a gear *H*, which meshes with a small annular pinion *G*, rigidly connected to the frame of the press and 70 through which the trunnion of the roll freely passes. By this arrangement of devices while the roll *A* revolves the train of gears revolves therewith, moving concentrically around pinion *G*, and a slow rotative movement is given 75 to gear *J*—about, say, one revolution for three of the roll. This movement of gear *J* through the pitman and dogs imparts a partial movement to roller *B*, as is obvious, the amount of the rotative movement of roller *B* being regulated by the position of the pin *k*, which can be set so as to vary the throw of dog *L*. By this construction the ink is continuously agitated within the roll, is kept perfectly free from dust, is disseminated on the face of the 85 roll, and lessens the cost of the inking apparatus, as the ink-fountain becomes also a disseminating or distributing roll.

In the practical construction of the ink-fountain the roll is made in two parts, so as 90 to facilitate the insertion and fitting of the ductor-roller or valve and to enable the roll to be cleaned, if found necessary.

Having described my invention, what I claim as new, and desire to secure by Letters 95 Patent, is—

1. The combination of the hollow ink-holding slotted roll, a revolute roller journaled therein and occupying the slot thereof, the ratchet-wheel, movable pawl, its operating-le- 100

ver, and gearing for intermittently revolving said roller independently of its revolution by and with the roll, substantially as and for the purpose specified.

- 5 2. The combination of the hollow ink-holding roll having a longitudinal slot, the roller journaled in the ends of said roll and lying in the slot thereof, the ratchet on the end of said roller, the dog engaging the same, the 10 pitman, and revoluble gears mounted on the end of the rolls for operating the said dog,

and the fixed gear for operating the said revoluble gears, substantially as and for the purpose set forth.

In testimony that I claim the foregoing as 15 my own I affix my signature in presence of two witnesses.

JOSEPH L. COX.
